UNITED STATES PATENT OFFICE.

ELIHU THOMSON, OF SWAMPSCOTT, MASSACHUSETTS, ASSIGNOR TO GENERAL ELECTRIC COMPANY, A CORPORATION OF NEW YORK.

INTERNAL-COMBUSTION ENGINE AND METHOD OF OPERATING SAME.

1,096,405.

Specification of Letters Patent.

Patented May 12, 1914.

Application filed March 29, 1906. Serial No. 308,670.

To all whom it may concern:

Be it known that I, ELIHU THOMSON, a citizen of the United States, residing at Swampscott, in the county of Essex and 5 State of Massachusetts, have invented certain new and useful Improvements in Internal-Combustion Engines and Methods of Operating the Same, of which the following is a specification.

10 My invention relates to an internal combustion engine of the type in which the fuel charges are self-ignited, and its object is to combine the advantage of self-ignition, as in the Diesel engine, with that 15 of combustion of the charges at a comparatively high initial pressure without the necessity of the objectionably high compression essential in the Diesel cycle. The pressure of compression in the Diesel engine is about 550 20 lbs. per square inch, and the heat developed by compression of the air to this extent is utilized to fire the fuel when injected into the compressed air. To operate with such a high compression requires very exacting 25 workmanship in the construction of the engine, and at the best considerable piston-ring trouble, or leakage, is sooner or later experienced, thus affecting the efficiency. Furthermore, to obtain the proper fly-wheel 30 effect the operating parts have to be large and heavy, so that as a consequence, the size of the engine compared with the output is disproportionately large. With the present invention, I overcome these objections 35 by employing a much lower compression which, for instance, may be from 250 to 300 lbs. per square inch. The piston on its in-stroke is adapted to compress the air charge to a pressure of about 150 lbs. This pressure is also established in a supplemental combustion or pre-ignition chamber arranged at the head of the piston cylinder and in open communication with the combustion chamber or clearance of the latter. 40 Into this chamber, whose walls are initially heated by applying a torch-flame thereto, a charge of fuel is injected, which vaporizes and mixes with air entering from the cylinder so that it self-ignites at a definite 45 point in the compression stroke. The flaming gases rush into the cylinder and mix with the compressing air charge, resulting in increasing the pressure and temperature; the former increasing to about 250 lbs. and

the latter to a degree that is sufficient to 55 insure firing of the main fuel charge that is subsequently sprayed into the burning mass. Obviously, the quantity of air constituting the air charge is largely in excess of that consumed by the initial or supplemental combustion, so that the proper proportion of oxygen will be present to produce complete and economical combustion of the main fuel charge. The main fuel charge is injected at or a little after the 60 time the piston passes or has passed the inner dead center. An engine operating according to this method has an indicator diagram which from the beginning of the compression stroke shows a gradual rise in pressure in an adiabatic curve to about 150 lbs., an abrupt increase at the time of combustion of the supplemental charge to about 250 lbs., and a continued increase owing to combustion, and other compression to 65 approximately 300 lbs. At this point the main fuel charge is injected and fired, showing a rise to maximum pressure. On the power stroke the diagram shows a sustained pressure over the first portion of 70 the stroke during the continuation of the combustion and thereafter a falling off to 75 the end of the stroke.

The invention is applicable to engines having one, two or more cylinders and operating on either the two-stroke or the four-stroke cycle, the fuel supply system being organized in each case to supply the fuel charge at the proper time. In the four-stroke engine the scavenging would be done 80 in the usual manner—during the in-stroke succeeding the power stroke, whereas in the two-stroke engine the cylinder would be scavenged by pumping fresh air into the same during the exhaust period, the residual 85 air constituting the air charge to be compressed during the in-stroke.

The supplemental fuel charge is preferably so proportioned that the impulse resulting from the combustion will be such as 90 to keep the engine operating while running light. By means of a suitable load-responsive device the main fuel supply may be cut into or out of operation, or the fuel charge quantitatively varied from time to 95 time to meet changing conditions of operation. The supplemental fuel supply is maintained substantially constant so that the

5 combustion in the supplemental combustion chamber continues uninterrupted. Besides keeping the engine operating this ignition in the supplemental chamber serves to keep the walls hot and hence the engine ready for regular duty at all times.

10 For a more detailed understanding of the invention, attention is directed to the following description taken with the accompanying drawings, and to the features of novelty pointed out in the claims appended hereto.

15 In the accompanying drawings which illustrate one of the embodiments of the invention, Figure 1 is a longitudinal section of an engine of the four-cycle type with the improvements applied thereto; Fig. 2 is a top view of the engine; and Fig. 3 is a detail section of the cylinder head and 20 attached parts.

25 Referring to the drawings, 1 represents a cylinder of the water-jacketed construction having a clearance or combustion chamber 2, and in which reciprocates the piston 3. The piston is connected to a crank-shaft 4 which carries a fly-wheel 5, by means of the connecting rod 6. Arranged at the head of the cylinder is a hollow, spherical, supplemental combustion chamber 7 having 30 free communication with the clearance or combustion chamber 2. This chamber 7 is unjacketed so that the walls thereof may be initially heated by a torch and kept heated by the successive combustion within it to a 35 temperature sufficient to spontaneously ignite fuel charges delivered thereto.

40 Since the engine is of the four-cycle type, air inlet and exhaust conduits 8 and 9, respectively (Fig. 2) are arranged at the head of the cylinder and each is controlled by a mechanically actuated valve 10, only the exhaust valve being shown in the sectional figure. Also arranged at the head of the cylinder is a spraying device 11 which 45 sprays the main charge of fuel into the cylinder or combustion chamber thereof. Fuel is supplied to the supplemental chamber through a supply pipe 12 which terminates in a sprayer 12^a, and to the main sprayer 11 through a supply pipe 13. Any suitable source of supply may be employed but I prefer to use a pump 14 common to both supply pipes. The plunger 15 of the pump receives motion from a cam 16 arranged on 50 a secondary or half-speed shaft 17 so that the pump delivers its charge every fourth stroke of the engine piston. The pump draws its supply from a suitable source through the suction pipe 18 controlled by 55 the suction valve 19. Separate discharge valves 20, 21 control respectively, the supply pipes 12 and 13. The connection between the pipe 12 and the pump is arranged at some distance from the head of the pump cylinder with which head the pipe 13 con-

nects so that during the first part of the discharge from the pump, fuel is delivered to the supplemental combustion chamber, and during the remaining portion of the stroke, to the main sprayer 11, the object of which 70 relation is more fully set forth hereinafter.

75 The suction stroke of the pump is performed by a compression spring 22 arranged between abutments 23, the discharge stroke compressing the spring so that the piston is withdrawn when the cam 16 passes from under the plunger actuator or push rod 24. In order that the pressure in the main supply pipe 13 may not become excessive, a by-pass 25 is provided which is 80 controlled by a release valve 26.

85 For spraying the fuel into the clearance or combustion chamber 2, air under compression is employed but other gases might be used if desired, the essential function of the air or gas being merely to atomize or spray the fuel and convey it to the cylinder. This air is supplied by a compound pump having a low pressure piston and cylinder 27 and a high pressure piston and cylinder 28. The pump piston is operated from an eccentric 29 on the crank shaft by a cross-head and connecting rod connections 30. The low pressure plunger draws its supply through a suction valve 31 and discharges 95 into a low pressure chamber 32 through the valve 33. The high pressure plunger draws its supply from the chamber 32 through a suction valve 34 and discharges into a high pressure reservoir 35 through the delivery 100 valve 36. The fuel and air supplies are delivered to the sprayer through conduits 37 and 38, respectively, which are controlled by needle valves 39 and 40. The sprayer comprises a plurality of superposed perforated 105 gauze diaphragms 41 through which the fuel and air are discharged, the same serving to mix the two and also to prevent back firing from the combustion chamber 2. The fuel and air pumps are of such size as to deliver 110 the desired amount of fuel and air at a pressure of about 300 lbs. to the square inch, such pressure being that attained in the combustion chamber 2 at the time the main fuel discharge is injected. At the outer end of 115 each needle valve is a yoke 42 in which engages the free end of a lever 43, Figs. 2 and 3. The levers 43 are fulcrumed on the standards 44 at a point 45 and extend over the cam shaft 46 mounted in standards 47. 120 This shaft is adapted to be driven at half the speed of the crank-shaft by any suitable mechanism (not shown), and is provided with a cam sleeve 48 having cams which engage with the rollers 49 on the levers where- 125 by the levers are periodically raised to open the needle valves. Attached to the yokes 42 of the needle valves are stems 50 that extend through the guide openings in the frame 51 on the cylinder head. Around 130

each stem and abutting at one end against the yoke and the other against the frame is a compression spring 52 which operates to close the needle valve. In order to vary the lift of the valves, the cam sleeve 48 is adjustable along the cam shaft 46 to which it is feathered so as to present different portions of the cams to the rollers 49 of the valve actuating levers 43 in a well known manner. For this purpose a cam shipper or controller 53 is provided, comprising a lever which is fulcrumed on the standard 44 at 54 and engages at its inner end the collar 55 attached to the cam sleeve. On the controller is arranged a latch 56 that engages with the notched sector 57 and holds the controller in any desired position.

The fuel and air pumps are adapted to deliver sufficient fuel and air for the maximum demand. When, however, the needle valves are so adjusted as to permit less than the maximum discharge from the pumps to be delivered to the engine, the surplus of fuel and air is by-passed. The fuel is by-passed through the valve 26, Fig. 1, and pipe 25, and the air is by-passed through the passage or conduit 58, between the high and low pressure chambers 32 and 35. The by-pass is controlled by a regulator or governing means which comprises a needle valve 59 attached to a diaphragm 60. The diaphragm is subjected to the air pressure in the high pressure chamber 35 by means of the conduit 61 communicating with the by-pass 58 and the diaphragm containing chamber 62. The diaphragm is weighted by a spring 63 that acts through the bell-crank lever 64 to which it is attached. One arm of the lever impinges upon the outer end of the needle valve that extends through the wall of the diaphragm chamber. By this arrangement the spring urges the valve against its seat to close the by-pass, while the diaphragm acts against the tension of the spring when the air pressure exceeds a predetermined amount to open the by-pass. When the by-pass is opened the high pressure pump discharges into the high pressure chamber 35 and the air passes therefrom through the by-pass back to the low pressure chamber. In order to prevent the pressure in the low pressure chamber 32, due to the pump 27, from becoming excessive the suction valve 31 is adapted to be held open by means of a lever 65 linked to the bell-crank lever 64 so that simultaneously with the opening of the by-pass valve 59 the suction valve 31 will be opened. Hence the low pressure pump draws in air through the suction valve and discharges it again therethrough without delivering any to the low pressure chamber.

The speed of the engine is automatically controlled by means of the centrifugal governor 66 arranged on the half-speed shaft 17

which shifts the cam 16. By this means the stroke of the fuel pump and hence the quantity of fuel delivered thereby to the engine cylinder will be automatically varied according to the demands. For simplicity 70 the air charges are substantially constant, so that by varying the fuel charges the resulting combustible mixture will vary somewhat as to its richness to suit the demands for power.

The air inlet and exhaust valves 10 are both mechanically operated. A bell crank lever 67 for each valve is mounted on standards 68 extending from the head of the cylinder, Fig. 3. The levers are periodically oscillated by cams 69 arranged on the cam shaft 46 which cause the ends 70 of the bell-crank levers to be depressed so as to open the valves. The valves are closed by means of springs 71 arranged around the stems 72 and confined between a stationary abutment 73 and the movable abutment or head 74 on the upper ends of the stems. The cams for actuating the levers 67 are so related that the valves will open in proper sequence.

The operation is as follows: The walls of the supplemental combustion chamber are heated to the proper temperature by applying the torch thereto. The engine is next cranked so as to draw in a charge of air and 90 to start the pumps. The fuel pump delivers first to the supplementary combustion chamber, simultaneously with the in-stroke of the engine piston. Air in the engine cylinder is thus compressed and a portion thereof passes to the supplementary chamber and is carbureted by the fuel delivered thereto by the pump. By reason of the heated walls of the chamber the fuel mixture spontaneously ignites, this taking place preferably slightly 95 before the completion of the compression stroke. During the time the fuel is discharging in the supplementary chamber the needle valve is closed so that the fuel pump is delivering only to the supplementary 100 chamber. After the initial combustion, however, the needle valve is opened so that the pump on continuation of its discharge stroke, delivers fuel to the main sprayer 11. Simultaneously with the stroke of the fuel 110 pump air under pressure passes from the chamber 35 and is admitted to the main sprayer 11 in the proper amount to effectively spray the fuel into the flaming products of combustion that have in the meantime entered the main combustion chamber 2 from the supplementary chamber 7. This produces the power stroke. As the air pump is driven direct from the engine shaft, it 115 will have two strokes compared to the one of the fuel pump so that the proper air pressure can be obtained in the chamber 35. By suitably adjusting the cam sleeve 48 the main fuel charge can be delivered to the engine at the proper time and the period of 120 125 130

admission can be varied so as to obtain combustion during a greater or lesser portion of the out-stroke. After the power stroke the exhaust valve opens and permits the products of combustion to be discharged during the in-stroke of the piston and on the succeeding out-stroke the air-admission valve opens to permit a charge of atmospheric air to be drawn into the cylinder that is compressed on the next in-stroke of the piston and the cycle of operation is repeated. In case the speed varies, due to load changes, the governor varies the amount of fuel delivered to the engine so that the power derived from combustion of the resultant mixture of air and fuel will be automatically changed in accordance with the demand.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is,

1. The method of operating an internal combustion engine which consists in admitting air to the cylinder, compressing the air therein to a moderate degree, introducing into the cylinder burning gases and products of combustion under a pressure superior to the compression pressure during the later portion of the compression stroke to raise the temperature of the compressed air charge to ignition value, and subsequently introducing a fuel charge into the cylinder at or near the inner end of the piston stroke which is ignited by the temperature of the gases contained therein.

2. The method of operating internal combustion engines, which consists in supplying air to the cylinder, compressing the air therein to a pressure less than that necessary for igniting the fuel charge by the heat of compression, introducing flaming gases into the cylinder during the later portion of the compression stroke to increase the temperature and pressure of the contents of the cylinder, and subsequently introducing a fuel charge into the contents of the cylinder in the presence of said flaming gases so that the charge is ignited thereby.

3. The method of operating internal combustion engines having a combustion chamber connected with the interior of the engine cylinder, which comprises supplying air to the cylinder, compressing air in the chamber and cylinder to a pressure less than that necessary for igniting the fuel charge by the heat of compression, introducing fuel into the chamber from which the burning gases pass into the cylinder during the compression stroke to increase the temperature and

pressure of the contents of the cylinder, and subsequently introducing a fuel charge into the contents of the cylinder at or near the completion of the compression stroke so that the charge is ignited by said burning gases. 70

4. The method of operating internal combustion engines having a separate combustion chamber in open communication with the interior of the cylinder, which consists in supplying air to the cylinder and chamber, compressing air in the cylinder and chamber to a pressure substantially less than that necessary for igniting the fuel charge by the heat of compression, introducing fuel into the air in the chamber near 75 the end of the compression stroke and igniting the contents of the chamber so that flaming gases pass from the chamber into the cylinder to increase the temperature and pressure of its contents, and subsequently introducing a fuel charge into said contents, the charge being ignited by the flaming gases. 80

5. The method of operating internal combustion engines, which comprises supplying 90 air to the cylinder, compressing air in the cylinder and its clearance space to a degree less than that required for igniting the fuel charge by the heat of compression, introducing flaming gases into the compressed air 95 to increase the temperature and pressure of the contents of the cylinder, and subsequently spraying a fuel charge into the clearance space of the cylinder at or near the completion of the compression stroke by 100 means of compressed air at a pressure higher than the pressure in the cylinder, said charge being ignited by the flaming gases.

6. The method of operating internal combustion engines having a heated retort or combustion chamber in constant and open communication with the working cylinder, which consists in compressing air unmixed with fuel in the cylinder and chamber to a 110 temperature below the igniting temperature of the fuel, feeding fuel into the air in the combustion chamber where it is caused to ignite solely by contact with the hot walls thereof, and forcing fuel into the 115 working cylinder against the compression pressure where it is ignited by the burning gases issuing from the combustion chamber.

7. The method of operating internal combustion engines having a combustion chamber connected with the interior of the cylinder, which comprises supplying air to the cylinder, compressing air in the cylinder to a degree less than that necessary for igniting the fuel charge by the heat of compression, igniting an explosive mixture in the chamber during the later part of the compression stroke so that flaming gases pass from the chamber to the cylinder, and subsequently introducing a fuel charge into the 120 125 130

cylinder at or near the inner limit of the movement of the piston, the charge being ignited by said flaming gases.

8. The method of operating internal combustion engines having a combustion chamber in open communication with the working cylinder, which consists in introducing fuel and air into said chamber during the latter part of the compression stroke, igniting the contents of the chamber by means of the hot walls thereof, said contents passing into the work cylinder to raise the temperature of the air therein and subsequently delivering a fuel charge into the cylinder adjacent the discharge of the combustion chamber to mingle with and be ignited by the hot gases discharged from said chamber.

9. The method of operating internal combustion engines having a combustion chamber in open communication with the engine cylinder, which comprises separate forcing air and a small amount of fuel into the chamber during the latter part of the compression stroke of the engine, igniting the mixture of air and fuel in the chamber, and subsequently forcing a fuel charge into the body of hot flaming gases delivered to the cylinder from the chamber.

10. The method of operating internal combustion engines having a heated retort or combustion chamber in constant and open communication with the working cylinder, which consists in compressing air unmixed with fuel in the cylinder and retort to such a pressure that its temperature is below the igniting point of the fuel, delivering a charge of fuel to the retort where it mixes with the compressed air and is ignited as it enters by the hot walls of the retort, said charge being sufficient to drive the engine when there is no load, and forcing fuel into the compressed air in the working cylinder where it is ignited by the hot gases issuing from the retort due to the earlier ignition.

11. The method of operating internal combustion engines having a combustion chamber communicating with the engine cylinder, which comprises igniting in the chamber a relatively fixed amount of explosive mixture, and introducing the flaming gases from the chamber into the cylinder during the compression stroke and subsequently feeding a fuel charge into the cylinder to mingle with and be ignited by the flaming gases discharged from the chamber, said charge being proportioned to the load on the engine.

12. In an internal combustion engine, the combination of a cylinder having an air inlet and a clearance space, a piston in the cylinder which on an instroke compresses a charge of air in the cylinder and clearance space to a degree considerably below that necessary for igniting the fuel charge by the heat of compression, a combustion chamber from

which flaming gases enter the cylinder, an open conduit between the cylinder and the chamber whereby compression is established in the latter during the compression stroke of the piston, means for injecting fuel into the compressed air in the chamber prior to the end of the compression stroke, the mixture being ignited by the hot walls of the chamber and passing into the cylinder to raise the pressure and temperature of its contents, a spraying device arranged to supply fuel to the clearance space of the cylinder, and means supplying air and liquid fuel to the spraying device to deliver a fuel charge to said space, the hot gases from the combustion chamber igniting the mixture in the cylinder to produce the power stroke.

13. In an internal combustion engine, the combination with a cylinder having an air inlet and a clearance space, of a piston which on an instroke compresses a charge of air in the cylinder and clearance space to a degree considerably below that necessary for igniting the fuel charge by the heat of compression, a combustion chamber communicating with the interior of the cylinder whose walls are heated by the combustion in the chamber so that they ignite fuel delivered to the chamber, said chamber discharging flaming gases into the cylinder for increasing the pressure and temperature of its contents, means for spraying fuel into the chamber prior to the end of the compression stroke to produce a body of flaming gases therein, a sprayer for spraying fuel into the cylinder, a source of fuel supply connected with the sprayer, a source of compressed air supply also connected with the sprayer, and means for opening communication between said sources and the sprayer at or near the inner end of the piston travel so that the mixture is fired by said flaming gases as the fuel is sprayed into the contents of the cylinder.

14. In an internal combustion engine, the combination of a cylinder having an air inlet and a clearance space, a piston which on an instroke compresses a charge of air in the cylinder and clearance space to a degree considerably below that necessary to ignite the fuel charge by the heat of compression, a combustion chamber whose walls are heated by the combustion therein so as to ignite the fuel delivered thereto and to deliver flaming gases to the cylinder for increasing the pressure and temperature of its contents, means for spraying fuel into the chamber near the end of the compression stroke to produce a body of flaming gases therein, a sprayer for spraying fuel into the cylinder, a source of fuel supply connected with the sprayer, a source of compressed air supply also connected with the sprayer, a governor for controlling the pressure of the source of compressed air, and means for establishing communication between said sources and the

sprayer at or near the inner end of the piston travel and after the flaming gases have entered the cylinder so that said gases fire the mixture as the fuel is sprayed into the 5 contents of the cylinder.

15. In an internal combustion engine, the combination of a cylinder having an air inlet and a clearance space, a piston which on the instroke compresses a charge of air in 10 the cylinder and clearance space to a degree considerably below that required to ignite the fuel charge by the heat of compression, a combustion chamber whose walls are heated by the combustion therein so as to ignite 15 fuel delivered thereto and to deliver flaming gases to the cylinder for increasing the pressure and temperature of its contents, means for spraying fuel into the chamber near the end of the compression stroke to produce a 20 body of the flaming gases therein, a sprayer for spraying fuel into the cylinder, a pump driven by the engine which supplies fuel to the sprayer, a governor for the pump, an air pump also driven by the engine which 25 supplies air to the sprayer, separate valves for the fuel and air supplies, and means for opening the valves at or near the inner limit of the piston travel and after the flaming gases have entered the cylinder so that said 30 gases will ignite the mixture as the fuel charge is sprayed into the contents of the cylinder.

16. In an internal combustion engine, the combination with a cylinder having an air 35 inlet and a clearance space, of a piston which on the instroke compresses a charge of air in the cylinder and clearance space to a degree considerably below that necessary to ignite the fuel charge by the heat of compression, a combustion chamber whose walls are heated by the combustion therein so as to 40 ignite fuel delivered thereto and to deliver flaming gases to the cylinder to increase the pressure and temperature of its 45 contents, means for spraying fuel into the chamber near the end of the compression stroke, a sprayer for spraying fuel into the contents of the cylinder after their temperature and pressure have been increased 50 by said flaming gases, a pump driven by the engine which supplies fuel to the sprayer, a governor for the fuel pump, an air pump also driven by the engine which supplies air to the sprayer, and a governor for the 55 air pump.

17. In an internal combustion engine, the combination with a cylinder having an air inlet and a clearance space, of a piston which on an instroke compresses a charge of 60 air in the cylinder and clearance space to a degree considerably below that required for igniting the fuel charge by the heat of compression, a combustion chamber whose walls are heated by the combustion therein so as 65 to ignite fuel delivered to the chamber and

to deliver flaming gases to the cylinder for increasing the pressure and temperature of its contents, a sprayer for spraying fuel into the chamber near the end of the compression stroke, a sprayer for spraying fuel into the 70 cylinder, a pump driven by the engine which supplies fuel to both sprayers, a speed responsive device which controls the delivery of fuel to the cylinder sprayer without affecting the supply to the other sprayer, an 75 air pump also driven by the engine which supplies air to the cylinder sprayer, a governor for the air pump which is controlled by the pressure of the air delivered thereby, 80 separate valves for the fuel and air supplies, and means for opening the valves while the piston is near the inner end of its travel and after the flaming gases have entered the cylinder so that said gases will ignite the mixture as the fuel which is sprayed into the 85 cylinder.

18. In an internal combustion engine, the combination of a cylinder having a clearance space, a valved port through which air is admitted to the cylinder, a combustion chamber in permanent open communication with the clearance space, a piston in the cylinder which on an instroke compresses air in the clearance space and the chamber to a degree considerably below that necessary for igniting the fuel charge by the heat of compression, means discharging fuel into the compressed air in the chamber where it is ignited to form a body of flaming gases therein, fuel and air pumps discharging mixed fuel and 100 air into the cylinder subsequently to the ignition of the contents of the chamber so that the mixture is ignited by the flame from said chamber, and means for regulating the admission of the fuel charge to the cylinder 105 as the load changes.

19. In an internal combustion engine, the combination of a cylinder, means for admitting air to the cylinder, a piston that compresses air in the cylinder on an inward 110 stroke to a moderate degree, means admitting burning gases to the cylinder to raise the temperature of the air therein to a value above the igniting temperature of the fuel, a device for spraying fuel into the cylinder 115 after the temperature of the air therein has been raised to ignition value, a pump driven by the engine for compressing air, a fuel pump driven by the engine, a speed governor, means controlled by the governor for varying the effective delivery of the fuel pump, conduits for delivering air and fuel from the pumps to said device, and cam means driven by the engine that controls the action of said device and causes it to spray a 120 fuel charge into the cylinder at or near the completion of the compression stroke.

20. In an internal combustion engine, the combination of a cylinder having a combustion chamber in open communication with 125

the interior of the cylinder, means for supplying air to the cylinder, a piston in the cylinder that compresses the air therein on an inward stroke, a device for spraying fuel 5 into the cylinder, a pump driven by the engine for compressing air, a fuel pump, conduits for delivering air and fuel from the pumps to said device, a conduit for delivering fuel from the pump to the combustion chamber, means driven by the engine 10 for actuating the fuel pump to deliver fuel to the combustion chamber during the latter portion of the compression stroke of said piston to be ignited therein by the walls of 15 said chamber that are kept hot by the combustion of its contents, and cam means driven by the engine that controls the action of said device and causes it to spray a fuel charge into the cylinder at or near the completion of the compression stroke to mingle 20 with and be ignited by the flaming gases delivered by the combustion chamber.

In witness whereof, I have hereunto set my hand this twenty-sixth day of March, 1906.

ELIHU THOMSON.
